UNITED STATES PATENT OFFICE.

GEORGE W. BURNS, OF TROY, NEW YORK.

DESIGN FOR A FLOWER-BED SUPPORT FOR GRAVES.

SPECIFICATION forming part of Design No. 22,536, dated June 13, 1893.

Application filed May 15, 1893. Serial No. 474,355. Term of patent 7 years.

To all whom it may concern:

Be it known that I, GEORGE W. BURNS, of Troy, in the county of Rensselaer and State of New York, have invented a new and original 5 Design for Flower-Bed Supports for Graves, of which the following is a full, clear, and exact description.

Reference is to be had to the accompanying drawing, forming a part of this specification, 10 in which the figure represents in perspective, a flower bed support embodying my new design.

The design consists in the configuration and ornamentation shown.

15 Two transversely-ranging base pieces *a a* appear in the figure, each comprising top and bottom parallel members united near the ends by the vertical members *a'*. Ranging longi-

tudinally above the base pieces *a a* appears the rectangular box-like bed *b* having outwardly-projecting flange-like effects *c*, around the same at top and bottom and ornamented by symbols *d*, *d*, *d*. At the head appears the figure of an angel and an open book around the base or support of which appears scallop figures *e*. At the foot appears a smaller figure of an angel blowing a horn.

I claim—

The design for a flower bed support for graves herein shown and described.

GEORGE W. BURNS.
